WIRE PULLER

Filed June 25, 1928

FIG. 1.

FIG. 2.

FIG. 3.

UNITED STATES PATENT OFFICE

LEONARD H. WILLIAMS, OF FREEWATER, OREGON

WIRE PULLER

Application filed June 25, 1928. Serial No. 287,929.

This invention relates to wire pullers or tighteners and has particular relation to those devices intended for the use of linemen and for the use of farmers and others when 5 constructing fences.

In the construction of pulling machines for wire as fence wire and telephone wire, it is desirable to have a construction which will work equally well between two wire ends and 10 also between a post or pole cross arm and the wire to be drawn taut.

The primary object of this invention is the provision of an improved wire pulling device.

15 Another object of this invention is the provision of an improved wire pulling or stretching device with which it is possible to take up slack, hold the slack and then take up more slack.

20 Another object of this invention is the provision of such a stretching or pulling device which may be engaged with the side of a post opposite to the direction from which the wire is being pulled and which will permit of the

25 use of a hammer in the splicing, nailing, or stapling operation for securing the wire in place and without awkwardness on the part of the operator and without losing slack already taken up by the pulling device.

30 Another and further object of this invention is the provision of such an improved wire stretcher or puller that the tight wire may be brought up to a corner post and secured at a point where it is tight.

35 Other and further objects will be apparent to those skilled in the art from a reading of the complete specification and claims.

Referring to the drawing wherein I have illustrated an embodiment of my invention,

40 Fig. 1 is a side view of my invention shown in use in connection with a post.

Fig. 2 is a view similar to Fig. 1 but showing the use of the device where a fresh hold is taken on the wire for further tightening.

45 Fig. 3 is a view similar to Fig. 1 but showing the device in use for pulling two wire ends toward each other.

Fig. 4 is a cross sectional view on the line 4—4 of Fig. 1.

50 Similar reference characters refer to the

same or similar parts throughout the several views of the drawing.

In the drawing, an elongated body member 10 is provided throughout its length with the spaced holding devices 11 in the form of notches on one edge.

At one end of the elongated member 10 is an extension 12 which has a bent outer end 13 which forms a loop, the end pointing in the general direction of the length of the body portion. At the extreme end of the end portion 13 is a point 14 which is used to pierce a fence post, cross arm of a telephone pole or any other similar object to which it may be desirable to draw a wire.

65 Mounted on the elongated body member is a carriage 15 which has a portion surrounding or partially surrounding the elongated body member 10. This carriage has an outwardly extending arm 16 which, at its end 70 carries a wire gripping or holding device. This holding device comprises a bent-over end 17 which, with the end of the lever 18, exerts a grip on the wire.

75 Connected to the carriage 15 by the link 19 is a lever 20. This lever 20 is shown of a U-shape form, the two portions of the U passing on opposite sides of the elongated body member 10. In addition to the pin connection 21 which pivots the lever 20 and the link 19 together, the lever 20 is provided with a fulcrum which is in the form of a pin 22. This latter is so placed on the lever 20 that it may have selective engagement with the spaced holding devices 11 of the elongated member 10.

80 Within the body of the carriage and in position to engage the holding devices 11, is a backward movement prevention means in the form of a projection 23.

85 At the end of the elongated body member 10, is a guide-carrying arm 24, carrying a guide wheel 25, pivoted thereon. To secure the guide-carrying arm 24 in place, I have provided a bent end 26 to engage the edge of the elongated body member 10. The elongated body member 10 is also provided with a bent end 27 to engage the guide carrying arm 24. When these two angular bent ends 26, 27 with the bolt 28 effectually pre-

vent movement of the guide-carrying arm 24 relative to the body member 10. The guide wheel 25 is shaped like a pulley block sheave to receive and guide the wire to be pulled.

5 At the end opposite to the guide carrying arm 24 is a wire holding or gripping means comprising a lever 29 and an offset ear member 30. The latter may be conveniently formed by bending the end of the extension 12, the looped portion 13 being welded in place or riveted as at 31.

10 The lever is of such length that it may be folded over the body portion as indicated at 32 in Fig. 1.

15 In operation there are several methods of using the device. Let us assume that a single wire is to be pulled up to a post. The device is first placed with the point 14 in 20 the surface of the post opposite to the direction from which the wire is to be drawn. The slack is now taken out of the wire, the wire being placed in the wire holding means 17, 18, the latter being turned so that its 25 end adjacent the turned portion 17 will engage the wire. The wire contacting surfaces of the parts 17, 18 are roughened so as to better grip the wire.

20 With the wire properly held to the carriage as just described, the operator takes 30 the lever and causes the fulcrum pin 22 to engage one of the holding devices 11. The lever is now drawn back which moves the carriage forward. The projection 23 engages a holding device 11 as soon as the 35 pressure is released on the lever. The pin 22 is now caused to be engaged with a holding device 11 farther toward the post P. The operation is repeated until the wire is 40 sufficiently tight. After the first or second operation, the wire is put in the pulley sheave guide 25.

45 When the wire is sufficiently tight, it is brought over to the post P and nailed or stapled. A very convenient feature of my invention is the construction whereby the carriage may pass the post, the guide sheave 25 keeping the taut wire and pulling machine in proper relation.

50 By making the portion 13 of the loop long enough, the carriage 15 may be operated past the post. Since the carriage carries the wire with it, it will be clearly seen that the wire will lie close to the post when the carriage is 55 in the extreme position. When in this extreme position, the whole machine is swung on the point 14 as a center until the elongated body portion 10 is out of the way. The wire is now stapled in place.

60 If the wire should be still too slack after first reaching the extreme position adjacent the extension 12, the free end of the wire is brought around the extension 12 and fastened between the gripping surfaces of the parts 29 and 30. This holds the slack al-

ready taken up. By holding the pin 22 out of engagement from the holding devices 11 and swinging the lever 20 against the adjacent end of the carriage 15, by exerting pressure on the lever 20 (to the left in Fig. 2), the projection 23 may be released. The carriage may then be moved back adjacent the guide supporting member 24 or to such distance as the operator estimates will be necessary. The tightening operation is now repeated and when sufficiently taut, the wire is stapled or nailed as already described.

65 If it is desired to tighten two wires for the purpose of splicing, the wire ends are secured in the two wire holding or gripping means 17, 18, and 29, 30. The lever 20 is now operated to cause the carriage 15 to operate along the elongated body member 10 as already described. When the slack has been taken up, the splice is made in the usual manner.

70 It is believed to be clear to one skilled in the art that I have produced a wire pulling machine which will serve the double purpose of drawing two wires together and drawing one wire toward a cross arm or post. In addition, the feature of taking up slack, holding what has been taken up and then taking up more slack, is important since it permits of the use of a shorter elongated body portion than would otherwise be necessary. This means a lighter machine as a whole.

75 While I have shown and described in detail an embodiment of my invention, I desire to have it understood that this is merely illustrative and that modifications and changes may be made without departing from the spirit of my invention and within the scope of the appended claims.

80 Having described my invention, what I claim and desire to secure by Letters Patent is:

85 1. A wire pulling machine comprising an elongated body member having spaced holding devices therealong, a wire holding device 90 fixed relative to the body member, a pulling carriage movable along the body member and having means for engaging the holding devices, a wire holding device on the carriage, a link pivoted at one end on the carriage, 95 a lever having its end pivoted at the other end of the link and a fulcrum on the lever in position to successively engage the spaced holding devices of the body member, the link being of such a length that when the fulcrum 100 is disengaged from the holding devices, the lever can be pressed against the carriage to disengage the engaging means on the carriage from the holding devices, to release the tension on the wire.

105 2. A wire pulling machine comprising an elongated body member having spaced holding devices therealong, a pulling carriage mounted on the body member for movement therealong, a lever having connection with

the carriage and constructed to have a selective engagement with the holding devices, an extension on the body portion and having its outer end looped and pointing in the general direction of the length of the body portion, the open end of the loop being of a size to receive substantially all of the carriage when moved along the body member.

3. A wire pulling machine comprising an elongated body member having spaced holding devices therealong, a pulling carriage mounted on the body member for movement therealong, a lever having connection with the carriage and constructed to have selective engagement with the holding devices, an extension on the body portion and having its outer end looped and pointing in the general direction of the length of the body portion, the open end of the loop being of a size to receive substantially all of the carriage when moved along the body member.

4. A wire pulling machine comprising an elongated body member having spaced holding devices therealong, a pulling carriage mounted on the body member for movement therealong, a lever having connection with the carriage and constructed to have selective engagement with the holding devices, the connection comprising a link connected at one of its ends to the carriage and at the other end to the lever, an extension on the body portion and having its outer end looped and pointing in the general direction of the length of the body portion, the open end of the loop being of a size to receive substantially all of the carriage when moved along the body member.

5. A wire pulling machine comprising an elongated body member having spaced holding devices therealong, a pulling carriage mounted on the body member for movement therealong, a lever having connection with the carriage and constructed to have selective engagement with the holding devices, the connection comprising a link connected at one of its ends to the carriage and at the other end to the lever, an extension on the body portion and having its outer end looped and pointing in the general direction of the length of the body portion, the open end of the loop being of a size to receive substantially all of the carriage when moved along the body member, and a wire-alining guide extending from the end of the body member opposite to the extension.

6. A wire pulling machine comprising an elongated body member having spaced holding devices therealong, a wire holding device at one end of the body member, a pulling carriage mounted on the body member for movement therealong, means on the carriage for engaging the spaced holding devices, to prevent backward movement during the tight-

ing operation, a lever having connection with the carriage and constructed to have selective engagement with the holding devices, the connection comprising a link connected at one of its ends to the carriage and at the other end to the lever, an extension on the body portion and having its outer end looped and pointing in the general direction of the length of the body portion, the open end of the loop being of a size to receive substantially all of the carriage when moved along the body member.

7. A wire pulling machine comprising an elongated body member having spaced holding devices therealong, a wire holding device at one end of the body member, a pulling carriage mounted on the body member for movement therealong, means on the carriage for engaging the spaced holding devices, to prevent backward movement during the tightening operation, a lever having connection with the carriage and constructed to have selective engagement with the holding devices, the connection comprising a link connected at one of its ends to the carriage and at the other end to the lever, an extension on the body portion and having its outer end looped and pointing in the general direction of the length of the body portions, the open end of the loop being of a size to receive substantially all of the carriage when moved along the body member, and a wire-alining guide extending from the end of the body member opposite to the extension.

In testimony whereof I hereunto affix my signature.

LEONARD H. WILLIAMS.
